Max Boltuch
INVENTOR

BY Louis Barnett

ATTORNEY

UNITED STATES PATENT OFFICE.

MAX BOLTUCH, OF NEW YORK, N. Y., ASSIGNOR TO LA SALLE BRASS & BRONZE WORKS, INC., A CORPORATION OF NEW YORK.

DESIGN FOR A STANCHION ELEMENT FOR AN ELECTRIC-LIGHTING FIXTURE.

Application filed March 13, 1929. Serial No. 30,457. Term of patent 3½ years.

To all whom it may concern:

Be it known that MAX BOLTUCH, a citizen of Poland, and resident of New York city, in the county of Kings and State of New York, has invented a new, original, and ornamental Design for a Stanchion Element for an Electric-Lighting Fixture, of which the following is a specification, reference being had to the accompanying drawing, forming part thereof, in which

Fig. 1 is a front elevation view of the stanchion element for an electric lighting fixture embodying the invention, and

Fig. 2 is a top plan view thereof.

I claim:

The ornamental design for a stanchion element for an electric lighting fixture as shown.

Dated New York city, Feb. 15, 1929.

MAX BOLTUCH.
